(57) **CLAIM**

The ornamental design for a notebook computer as shown and described.

DESCRIPTION

FIG. 1 is a bottom view of the notebook computer according to the claimed design, with the notebook computer in a closed position;

FIG. 2 is a front view of the notebook computer according to the claimed design, with the notebook computer in a closed position;

FIG. 3 is a rear view of the notebook computer according to the claimed design, with the notebook computer in a closed position;

FIG. 4 is a right view of the notebook computer according to the claimed design, with the notebook computer in a closed position;

FIG. 5 is a left view of the notebook computer according to the claimed design, with the notebook computer in a closed position;

FIG. 6 is a top view of the notebook computer according to the claimed design, with the notebook computer in a closed position;

FIG. 7 is a bottom-right rear perspective view of the notebook computer according to the claimed design, with the notebook computer in a closed position;

FIG. 8 is a bottom-right rear perspective view of the notebook computer according to the claimed design, with the notebook computer in an open position;

FIG. 9 is a top-left front perspective view of the notebook computer according to the claimed design, with the notebook computer in an open position;

FIG. 10 is an enlarged view of an area labeled “10” in FIG. 7;

FIG. 11 is an enlarged view of an area labeled “11” in FIG. 2; and,

FIG. 12 is a cross-sectional view taken along a cut plane indicated as “12-12” in FIG. 1.

(Continued)

The broken lines in FIGS. 1-12 depict portions of the notebook computer that form no part of the claimed design. The dot-dash broken line rectangles, lead lines, and characters “10” and “11” in FIGS. 2 and 7 depict the limits of the enlarged views shown in FIGS. 10 and 11, respectively, and form no part of the claimed design. The arrows, lead lines, and characters “12” in FIG. 1 show the cut plane for FIG. 12 and form no part of the claimed design. The hatching in FIG. 12 shows an interior of the notebook computer and not surface ornamentation.

1 Claim, 9 Drawing Sheets
